UNITED STATES PATENT OFFICE.

EDWARD E. GOOD, OF BLUFFTON, OHIO.

GEAR PULLER.

Application filed January 27, 1922. Serial No. 532,309.

To all whom it may concern:

Be it known that I, EDWARD E. Good, a citizen of the United States, residing at Bluffton, in the county of Allen and State 5 of Ohio, have invented new and useful Improvements in Gear Pullers, of which the following is a specification.

This invention relates to pushing and pulling implements, particularly to devices 10 for pulling off gears, pulleys and the like from their supporting shaft, and has for its object the provision of a novel device which is adapted for pulling off machine elements of this character by engaging externally 15 thereon.

An important object is the provision of a tool of this character which is adjustable whereby it may be operatively engaged upon 20 machine elements of widely different sizes, the matter of adjustment being a simple one and being very rapidly made.

Still another object is the provision of a device of this character which is provided 25 with a ratchet operated screw means for applying the necessary power for pulling off gears, pulleys and the like, the construction being furthermore such that binding of the power screw within the supporting and other portion of the device will be positively 30 prevented.

An additional object is the provision of a device of this character which will be simple and inexpensive in manufacture, highly efficient in use, rapid and positive in action, 35 durable in service and a general improvement in the art.

With the above and other objects and advantages in view, the invention consists in the details of construction to be hereinafter 40 more fully described and claimed, and illustrated in the accompanying drawings, in which:—

Figure 1 is a side elevation of the device with parts broken away and in section,

45 Figure 2 is a cross section on the line 2—2 of Figure 1,

Figure 3 is a cross section on the line 3—3 of Figure 1,

50 Figure 4 is a cross section on the line 4—4 of Figure 1,

Figure 5 is a detail section taken longitudinally of the device and showing the operating ratchet.

Referring more particularly to the drawings, the numeral 10 designates the body or housing of the device which is formed

trapezoidal in shape and which has a rectangular central opening 11 at opposite sides of which extend wings 12. At its larger end this frame or body is formed 60 with a hollow cylindrical extension 13 which has a smooth bore 14 and which has its outer periphery threaded.

Keyed or splined through this frame member 10 is the operating screw 15 which is of 65 course threaded throughout its length and which has one end formed with a concavity 16 and which has its other end carrying a swivelled head 17 for a purpose to be described. The recess end 16 of the screw is 70 designed for engagement against the end of the shaft from which the pulley, gear or other element is to be pulled.

Threaded upon the extension 13 of the frame or body is a nut member 18 formed at 75 one end with a frusto-conical flange 19 and provided at its other end with an operating head 20 which is shaped for convenient engagement within the operator's hand 80 whereby it may be turned with ease.

The numeral 21 designates the operating lever of the device which is formed at one end with an enlarged head 22 having a central opening 23 therein within which is rotatably engaged a ratchet 24 which has a 85 threaded bore 25 having screwed engagement upon the operating screw 15. The enlarged head 22 of the lever and the ratchet 24 are located within the opening 11 in the frame 10 as clearly shown. The enlarged 90 head 22 of the operating lever is also formed with an opening 26 and a recess 27 communicating therewith. The numeral 28 designates a pawl which is located within the head 22 and which has a stem 29 disposed 95 within the recess 27 and which is formed intermediate its ends with a knurled operating head 30 access to which may be had through the opening 26.

So that the device may be used for pulling 100 off gears, pulleys and the like, I make use of a plurality of arms 31 which terminate at their free ends in inwardly directed hooks 32 and which have their other ends formed with curved extensions 33 engaging back of the flange 19 on the nut member 18. These arms are pivoted at the corners of the frame 10 by suitable bolts indicated at 34.

In the operation of the device consisting 110 of the above mentioned parts, it is necessary to run out or retract the operating screw 15 and then screw down the nut member 18

upon the cylindrical extension 13 of the frame in order that the arms 31 will spread apart a sufficient distance that they may be engaged over the periphery of the gear, pulley or other similar machine element to be pulled. The nut member 18 is then unscrewed so that the flange 19 thereof engaging against the curved rear extensions 33 of the arms will cause the arms to swing upon 10 their pivot bolts 34 so that the hooked ends 32 will engage over and clamp upon the periphery of the machine elements to be drawn off. The operator then grasps the lever 21 and reciprocates it, or rather rocks 15 it back and forth whereupon the pawl 28 cooperating with the ratchet 24 will operate to rotate the latter and as this ratchet is screwed upon the screw 15 it will be apparent that it will result in longitudinal movement 20 of the screw owing to the fact that the screw itself is splined with respect to the frame 10 and cannot rotate with respect thereto. When the free end 16 of this operating screw engages against the end of the 25 shaft upon which the pulley or gear to be drawn off is mounted, it will be apparent that a powerful action or pressure will be exerted upon the pulley, gear or the like which will result in pulling it off from the 30 shaft. By grasping the operating head 30 of the pawl and lifting the pawl up out of engagement with the ratchet 24, I then reverse its position and subsequently allow it to drop back, it being apparent that the 35 ratchet mechanism may be caused to operate in either direction as may be found necessary.

From the foregoing description and a study of the drawings it will be apparent 40 that I have thus provided a simply constructed and consequently inexpensive de-

vice which will be highly efficient for use in pulling off gears, pulleys, drums and the like from shaftings and which is also adaptable for other purposes which may suggest 45 themselves. Owing to the simplicity of the construction and the fewness of the parts, it is apparent that there is nothing to get out of order and that the device should consequently have a long life and satisfactorily 50 perform all the functions for which it is intended.

While I have shown and described the preferred embodiment of the invention, it is of course to be understood that I reserve 55 the right to make such changes in the form, construction and arrangement of parts as will not depart from the spirit of the invention or the scope of the subjoined claim.

Having described my invention I claim:— 60

A puller of the character described comprising a frame formed with an opening and having a cylindrical externally threaded extension, the extension and the frame being formed with a smooth bore intersecting said opening; a plurality of arms pivoted upon the frame and terminating in hooks adapted for engagement with the element to be pulled, said arms being pivoted intermediate their ends and having the ends 70 opposite the hooks formed with cut out portions defining extensions, an operating screw splined through the frame, a nut member threaded upon said extension and having a tapered flange extending within the cut 75 out portions of the arms with its outer surface bearing against said extensions of the arms, a ratchet threadedly engaged upon said screw within said opening, and a pawl equipped lever for rotating the ratchet. 80

In testimony whereof I affix my signature.
EDWARD E. GOOD.
